UNITED STATES PATENT OFFICE.

CHARLES F. HOBSON, OF ST. HELENA, CALIFORNIA.

SAW-FILING DEVICE.

No. 870,883.

Specification of Letters Patent.

Patented Nov. 12, 1907.

Application filed December 12, 1906. Serial No. 347,444.

To all whom it may concern:

Be it known that I, CHARLES F. HOBSON, a citizen of the United States, residing at St. Helena, in the county of Napa and State of California, have invented new and useful Improvements in Saw-Filing Devices, of which the following is a specification.

My invention relates to machines for sharpening saws. Its object is to provide a machine which will do this work rapidly and efficiently; which will be adaptable to saws of all sizes and of all varieties of teeth, and which particularly will be adjustable equally well to cross-cut and rip saws.

The invention consists of the parts and the construction and combination of parts as hereinafter more fully described and claimed, having reference to the accompanying drawings, in which—

Figure 1 is a plan view of the invention. Fig. 2 is a section on line X—X, Fig. 1. Fig. 3 is a section on line 4—4, Fig. 1.

20 A represents a suitable supporting frame for the structure. This frame carries two reciprocating file frames 2, each carrying a set of files 3, the number of files in each set corresponding to half the number of teeth in the saw. One set of files is adapted to sharpen 25 all the teeth having their pitch in one direction and the other set of files to sharpen all the teeth pitched in the opposite direction: the two frames reciprocating in the same direction to permit the two sets of files to act alternately on the teeth.

30 Each file frame is in the form of a parallelogram having articulated or hinged sides and ends; the ends of each of these parallelogram frames sliding in a corresponding pair of hinged guides 4. These file frame guides 4 are hinged or pivoted at their inner ends as at 35 5, near the center of the support A; there being a pair of these guides on each side of the center of the machine and the guides being connected together at their outer ends by a link 6, so that the parallelism of the guides 4, and consequently of the end members of a corresponding 40 file frame, will be maintained. By having the frame guides jointed, and by making the file frames jointed in the manner shown, the files can be set at any angle with relation to the plane of the saw 7, so as to give any desired bevel to the teeth.

45 The positions of the file frames and guides therefor are adjusted and fixedly maintained in any desired position by suitable means as the locking devices 8, carried by the file frame guides engaging with the fixedly supported slotted parts 9; the slots in the latter 50 being concentric with the pivots 5.

The saw to be sharpened is supported in a suitable vise 10 arranged centrally of the machine and adapted to be adjusted vertically to bring the saw teeth into proper operative position with respect to the gangs of

files 3. This saw-vise is more fully illustrated in Fig. 55 2, in which it is shown as arranged to slide in vertical fixed guides 11 and is supported by a bracket 12 on a screw 13. This screw has a plain shaft portion suitably journaled in a fixed part of the frame A and carries on its lower end a beveled gear 14 meshed with a corresponding gear 15 on the adjusting rod 16. By means of a hand-wheel 17 the rod 16 is turned to raise or lower the saw-vise in the desired manner.

The vise is provided with spring-gripping-sides, which are drawn together to grip the saw by means of 65 a hand-wheel 18. Any suitable form of power may be employed to give the proper reciprocatory motion to the file-frames and files.

In the present instance I have shown each file frame as connected by a link 19 with a corresponding disk 70 20 journaled on a vertical pivot. The underside of each disk has a beveled gear portion 21 meshing a corresponding gear 22 on a shaft 23; each shaft 23 carries a gear 24; and these gears 24 are driven simultaneously in the same direction by engagement with a gear 25 75 on the operating shaft 26. In the present instance I have shown a crank 27 for operating the drive shaft 26.

In operation the saw to be sharpened is placed in the vise and locked. The file-frames and guides and files are suitably adjusted so that the several files in each 80 gang, will be in the proper position to cut the right bevel on the teeth. The inner side-bar of each file frame 2, that is that bar which carries the files is removable to permit other bars having files or having file holding means adapted to receive files, suited for 85 different kinds of saws: saws having a greater or less number of teeth, or the teeth being of different pitch or bevel. The design of the present invention is to use as many files in the two gangs as there are teeth in the saw, so that all the teeth will practically be filed 90 at one operation. Having adjusted the files and file-frames so that the files will give the desired bevel to the teeth, the file-frame guides are locked in position by the devices 8. The drive-shaft 26 is then set into motion and the saw is fed up to the files as fast as required by means of the hand-wheel 17 and its connections with the saw vise.

Having thus described my invention, what I claim and desire to secure by Letters Patent, is—

1. In a saw-filing device, the combination of a suitable 100 saw-support, two-jointed file-frames with file-holding means, each of said file-frames being substantially in the form of a parallelogram having its sides pivotally connected to its ends, one of said frames arranged on one side of the saw-support and the other frame arranged on the other side, adjustable guides in which the ends of said articulated saw-frames are slidably mounted, said guides being hinged at their inner ends and connected by links at their outer ends and provided with locking means, each articu- 105

2
lated saw-frame being angularly adjustable in unison with its guides, and means for reciprocating said file frames, said last-named means including a bevel gear mounted on a vertical axis beneath each saw-frame, a pitman connecting each gear and a respective frame, and driving-connections with said gears to impart an alternating reciprocating motion to said file frames, substantially as described.

5. 2. In a saw-filing device, the combination with saw sharpening means, of a saw-vise vertically-slidable relative thereto, a bracket engaging said vise, a screw passing

through the bracket and journaled in said support, a bevel gear fixed to the screw, and a journaled rod having a gear to mesh with the gear on the screw for vertically adjusting said vise.

In testimony whereof I have hereunto set my hand in 15 presence of two subscribing witnesses.

CHARLES F. HOBSON.
